US00D625746S

(12) **United States Design Patent**
Roberts

(10) **Patent No.:** **US D625,746 S**
(45) **Date of Patent:** **** Oct. 19, 2010**

(54) **PLASMA HAND TORCH**

(75) Inventor: **Jesse Roberts**, Cornish, NH (US)
(73) Assignee: **Hypertherm, Inc.**, Hanover, NH (US)
(**) Term: **14 Years**
(21) Appl. No.: **29/358,752**
(22) Filed: **Mar. 31, 2010**
(51) **LOC (9) Cl.** **15-09**
(52) **U.S. Cl.** **D15/144; D8/107**
(58) **Field of Classification Search** **D4/129, D4/138; D8/30, 54, 71, 80, 107, 303; D15/144.1, D15/144.2; 219/70, 138, 139, 140, 141, 219/142, 143, 144**

See application file for complete search history.

(57) **CLAIM**

The ornamental design for a plasma hand torch, as shown and described.

DESCRIPTION

FIG. 1 is a side view of a plasma hand torch having the new design;

FIG. 2 is a top view of the plasma hand torch of FIG. 1;
FIG. 3 is an end view of the plasma hand torch of FIG. 1; and,
FIG. 4 is a perspective view of the plasma hand torch of FIG. 1.

The dotted and/or broken lines depict environmental features, or the character or contour of the surfaces represented and are not a part of the claimed design.
